UNITED STATES PATENT OFFICE.

JOHN M. FEEDERS, OF BUFFALO, NEW YORK, ASSIGNOR TO FEEDERS MANUFACTURING COMPANY, INC., OF BUFFALO, NEW YORK, A CORPORATION OF NEW YORK.

CORE FOR RADIATORS.

Application filed June 8, 1925. Serial No. 35,711.

This invention relates to the core of radiators employed most generally for cooling the water of automobile gas engines. This invention has for one of its objects the provision of a core for radiators of this character which is constructed of strips of sheet metal so that the water conduits are formed integrally with the webs forming the radiating webs, thereby securing the most intimate connections between the water tubes and radiating webs and obtaining the maximum radiating efficiency. Another purpose of this invention is to reduce the number of parts in the core and thus facilitate the handling of the same and reducing the cost of manufacture.

Further aims of this invention are to so organize the elements of the same that when assembled they produce a core having much greater strength and capable of resisting destructive shocks and strains more effectively than cores of the type heretofore known.

In the accompanying drawings:—

Fig. 1, is a fragmentary front elevation of a radiator core embodying my invention.

Fig. 2, is a similar view of one section thereof.

Fig. 3, is a top plan view of one of the sections.

Fig. 4, is a bottom plan view of the same.

Figs. 5 and 6 are fragmentary perspective views of a radiator section viewed from the top and bottom, respectively.

Fig. 7, is a vertical transverse section of the core section taken on line 7—7, Fig. 3.

Figs. 8 and 9, are vertical longitudinal sections taken on the correspondingly numbered lines in Fig. 3.

Fig. 10, is a fragmentary vertical section, on an enlarged scale, showing a plurality of superposed sections in an assembled position, the section being taken on line 10—10, Fig. 3.

Similar characters of reference indicate like parts throughout the several views.

This radiator core consists of a plurality of superposed sections which form together a plurality of vertical water conduits or tubes and a plurality of horizontal air passages extending from the front side to the rear side of the radiator, whereby the air moving through these passages comes into contact with the exterior of the water tubes and carries away the heat from the water flowing through the tubes.

It is to be understood that in actual practice this core is suitably provided at its upper and lower ends with the usual water headers which connect with the water circulating system of the automobile engine for keeping the same from heating excessively.

Each core section is preferably constructed of a single sheet of metal which is bent so as to form a plurality of horizontal webs 22 which are arranged in a transverse row and with the longitudinal edges of the adjacent webs opposing each other, and a plurality of vertical pleats which preferably project downwardly from the webs and each of which has two longitudinal plies 23 having their corresponding pair of lower edges connected by a turn 24 while their corresponding pair of upper edges are connected, respectively, with the opposing edges of two adjacent webs.

Each pleat has each of its plies provided at suitable intervals with an outwardly bent portion forming one-half of a vertical tube 25 which is arranged opposite a similar half tube 25 in the companion ply of the respective pleat and forms therewith a whole or complete tube. The upper end of this tube is open and flush with the adjacent webs of the respective section. The lower end of each tube is also opened by displacing the stock of metal forming the turn of the pleat at the lower ends of the two half tubes so as to open the lower end of the tube and cause this displaced metal to form downward extensions 26 of the sides of the tube which terminate below the adjacent parts of the pleat turns. These extensions of each tube converge or taper slightly downward for a purpose which will presently appear.

The opposing edges of the webs on opposite sides of each pleat and the upper edge portions of the plies of each pleat are spaced apart to form a longitudinal groove or channel 27 therebetween.

In assembling a plurality of sections of this character for making a radiator core, each section is placed on top of another section to form a tier or pile of the desired height and the lower ends of the tubes of each section are inserted in the upper ends of the tubes of the next lower section, so as to form a telescopic joint therewith, the assembling of the tubes for this purpose be-

ing facilitated by the tapering or converging of the lower ends or extension of the tube sides, as shown at the center of Fig. 10. At the same time the turned lower edge portions of the pleats between the tubes are engaged with the grooves 27 at the upper ends of the pleats of the next lower section, as shown right in Fig. 10. By thus interengaging the tubes and pleats of adjacent sections 10 the same are reliably interlocked and firmly held against lateral displacement relative to each other.

When a sufficient number of sections have been thus assembled to produce a stack of 15 the required height the same are connected so as to prevent vertical displacement relative to each other and also to form leaktight joints between the tubes of the several sections and also between the plies of each 20 pleat for preventing the escape of water laterally from the tubes.

The connection between the plies of the respective pleats of each section and between the tubes of each section and adjacent sections 25 may be accomplished in various ways but preferably by coating the sheets of metal with solder or spelter before bending the same into the required shape and then subjecting the assembled stack of sections to 30 the heat of an oven, thereby causing the solder to melt and unite the contacting surfaces of the several units or sections, whereby leaktight joints are produced between them when the solder cools and hardens.

35 In order to obtain air passages between adjacent longitudinal rows of tubes which are substantially uniform in width and which are also tortuous lengthwise of the radiator the tubes are preferably so disposed 40 that each tube in one longitudinal row is arranged opposite the space between two tubes in an adjacent row, as shown in Figs. 3 and 4. By this means the air in passing through the air passages is compelled to 45 take a wavy or serpentine course or path on its way through the core, whereby the same is caused to take up more heat from the water passing through the tubes than would be the case if the air passages were 50 perfectly straight fore and aft.

As shown in the drawings the longitudinal rows of tubes contain alternately three and four tubes, but this number may vary as well as the height and width of the core 55 to suit the radiating capacity desired.

For the purpose of positively limiting the extent which the tubes may telescope and the turns of the pleats on one section may enter the grooves of another section the following 60 means are provided:—

Immediately below the bottom of some of the grooves 27 of each section and preferably at the front and rear ends of the same the companion plies of some of the pleats are 65 provided with an interlocking recess 28 and

projection 29 so as to form an upwardly facing shoulder 30 which extends entirely across the lower end or bottom of the groove, as shown at the left hand side of Fig. 10. The lower part of each half tube may also 70 be provided with an outwardly projecting circumferential bead 31 which engages with the upper end of the next lower tube into which it telescopes, as best shown in Figs. 1 and 10, thereby positively limiting the 75 extent which the several sections can telescope relative to each other and insuring a core which is uniform in shape and construction.

For the purpose of increasing the radiating capacity of the core the webs are provided with integral radiating fins or lugs 32 which project downwardly therefrom and into the air passages so that the air passing through the same will engage these obstructions in its path and thereby compel the same to take up more of the heat in the water and dissipate the same into the surrounding atmosphere. The radiating fins are preferably formed by producing a plurality of 80 openings 33 in each web and bending the stock of metal which is displaced during the formation of these holes so that the same remains integrally connected with the longitudinal sides of these holes, as shown in 85 Figs. 7 and 10. These holes are preferably of oval form and arranged with their major axis lengthwise of the radiator, thus furnishing a greater fin area for the air to strike 90 against and increasing the cooling capacity of the radiator accordingly. This cooling capacity is still further increased by staggering the several fin openings of each web 95 in a direction lengthwise of the path of the air, whereby the air is caused to ricochet 100 upon striking the fins which corresponds in arrangement to the companion holes, and thus materially aid in dispersing the heat 105 which has been absorbed by the water passing through the tubes.

This construction of core for radiators lends itself admirably for producing a radiator having great strength and capacity at low cost inasmuch as the sheet metal sections can be stacked and assembled successively in their proper position on the pile immediately upon coming from the forming machine after which it is only necessary to heat the batch of sections in order to melt the solder coating and thus unite the several 110 sections into one common mass and is ready for assembling with the water header and the enclosing casing.

I claim as my invention:—

1. In a radiator core having a plurality of 115 water conduits and a plurality of air passages arranged between adjacent water conduits, said core comprising a plurality of superposed sheet metal sections each of which is provided with a plurality of hori- 120

zontal webs and a plurality of vertical pleats, the plies of each pleat having one pair of their corresponding edges connected by a turn and their other corresponding edges 5 connected with the opposing edges of adjacent webs of the respective section, and each ply being provided with a half tube arranged opposite a similar half tube on the companion ply of the pleat and forming a whole tube therewith, and the tubes of each 10 section telescoping at the ends thereof adjacent to the turns of the respective pleats with those ends of the tubes of another section at the connection of the plies of the pleats with the webs thereof, and the opposing edges of 15 therewith, and the tubes of each section telescoping at the ends thereof adjacent to the turns of the respective pleats with those ends of the tubes of another section at the connection of the plies of the pleats with the webs 20 thereof, and the opposing edges of adjacent webs of each section and the adjacent parts of the respective plies being separated to form a groove therebetween which receives the turn of a pleat of another section 25 between the tubes thereof and the plies of a pleat being provided with an interlocking recess and projection arranged immediately at the bottom of a groove between adjacent webs and forming a stop shoulder which extends across the bottom of the 30 respective groove and is adapted to be engaged by the turn of a pleat seated in said groove. 80

2. A radiator core having a plurality of water conduits and a plurality of air passages arranged between adjacent water conduits, said core comprising a plurality of 25 superposed sheet metal sections each of which is provided with a plurality of horizontal webs and a plurality of vertical pleats, the plies of each pleat having one pair of their corresponding edges connected by a 30 turn in their other corresponding edges connected with the opposing edges of the adjacent webs of the respective sections, and each ply being provided with a half tube arranged opposite a similar half tube on the 35 companion ply of the pleat and forming a whole tube therewith, and the tubes of each section telescoping at the ends thereof adjacent to the turns of the respective pleats with those ends of the tubes of another section at 40 the connection of the plies of the pleats with the webs thereof, and the opposing edges of adjacent webs of each section and the adjacent parts of the respective plies being separated to form a groove therebetween which 45 receives the turn of a pleat of another section between the tubes thereof and the plies of a pleat being provided with an interlocking recess and projection. 100

3. A radiator core having a plurality of 50 water conduits and a plurality of air passages arranged between adjacent water conduits, said core comprising a plurality of superposed sheet metal sections each of which is provided with a plurality of horizontal webs and a plurality of vertical pleats, the plies of each pleat having one pair of their corresponding edges connected by a turn and their other corresponding edges connected with the opposing edges of 55 adjacent webs of the respective sections, and 60 each ply being provided with a half tube arranged opposite a similar half tube on the companion ply of the pleat and forming a whole tube therewith, and the tubes of each section telescoping at the ends thereof adjacent to the turns of the respective pleats with those ends of the tubes of another section at the connection of the plies of the pleats with the webs thereof, and the opposing edges of adjacent webs of each section and the adjacent parts of the respective plies being separated to form a groove therebetween which receives the turn of a pleat of another section between the tubes thereof and the plies of a pleat being provided with an interlocking recess and projection arranged immediately at the bottom of a groove between adjacent webs and forming a stop shoulder which extends across the bottom of the respective groove and is adapted to be engaged by the turn of a pleat seated in said groove and external beads arranged on said tubes, and the beads of the tubes on one section engaging with the ends of the tubes of another section. 115
